UNITED STATES PATENT OFFICE.

HERMAN J. DEMUTH, OF KIOWA, KANSAS.

PROCESS AND APPARATUS FOR DE-AERATING WATER.

1,267,191.

Specification of Letters Patent. Patented May 21, 1918.

Application filed January 30, 1917. Serial No. 145,489.

To all whom it may concern:

Be it known that I, HERMAN J. DEMUTH, a citizen of the United States, residing at Kiowa, in the county of Barber and State of Kansas, have invented new and useful Improvements in Processes and Apparatus for De-Aerating Water, of which the following is a specification.

This invention relates to a process and apparatus for deaerating and purifying water, being specially intended for use in connection with the manufacture of ice, and the invention consists briefly in subjecting the water to heat in a vacuum chamber, with drawing the air and gas by means of a vacuum pump or the like, and admitting the water vapor to a condenser from which the water of condensation is returned to the deaerating chamber for use in the manufacture of ice or for other purposes.

In the accompanying drawing forming part of this specification,

Figure 1 is a view of the apparatus in side elevation, parts being broken away.

Fig. 2 is an end elevation.

The water to be deaerated and purified is introduced into the deaerating chamber or reservoir 10 by means of inlet connection 12 and is there heated by the exhaust from a steam, oil or gas engine, the inlet for the exhaust steam being shown at 15 and the outlet at 16. Chambers 17 and 18 at the ends of the reservoir 10 are connected respectively with the inlet and outlet, and pipes 20 for the passage of the exhaust steam extend between said chambers 17 and 18.

The water being heated in chamber 10 in the manner indicated, and the air and

gases contained therein being expanded, 40 pass to the condenser 20 through pipe 21. The water of condensation returns from the condenser through the pipe 25 to the deaerating chamber 10, and the air and gas are withdrawn through pipe 26 by means of a 45 vacuum pump or the like.

A spraying device 27 is provided above the coils of the condenser for the usual purpose. The deaerated and purified water is finally withdrawn from reservoir 10 50 through pipe 30, which may lead to a pump connecting with the ice molds, or with any suitable receptacles.

One of the principal features of the invention is the treatment of the water, in the 55 manner described, in a chamber in which the pressure is below atmospheric pressure. A drip pan 35 is located below the condenser.

What is claimed is:—

In an apparatus of the class described, a reservoir, means for conducting a heating medium through a body of water therein, a plurality of condensing coils located adjacent to the reservoir, means for conducting 65 expanded air, gas and vapor from the reservoir to the coils, a spraying device above said coils, an exhaust connection for withdrawing air and gases and simultaneously reducing the pressure within the condensing 70 coils below atmospheric pressure, means for returning condensation from the coils to the reservoir, and means for withdrawing the purified and deaerated water from the reservoir. 75

In testimony whereof I affix my signature.

HERMAN J. DEMUTH.
